UNITED STATES PATENT OFFICE.

CLARENCE F. BREY, OF PHILADELPHIA, PENNSYLVANIA.

PIANO CONSTRUCTION.

Application filed January 12, 1925. Serial No. 1,767.

This invention relates to pianos, and is more particularly concerned with the type usually known as "uprights", its main object being to improve upon the casings of such pianos with a view toward overcoming the awkward appearance generally characteristic of them.

This desideratum I attain by employing a keyboard that is comparatively deep in a lateral direction and provided with legs so as to simulate on the whole, a spinnet type desk or console.

A further object of my invention is to enable in a piano casing of the character briefly outlined, separation of the key desk or console from the main portion of the casing containing the string frame, hammer action etc., for convenience in moving.

Other objects and attendant advantages will be readily apparent as the description proceeds of the typical embodiment of my invention, shown in the accompanying drawings whereof Fig. I is a perspective view of the improved piano.

Figs. II and III are similar illustrations of the respective casing sections detached from one another.

Figs. IV and V are fragmentary detail sectional views taken as indicated by the arrows IV-IV and V-V in Figs. I and IV, respectively.

In these illustrations, the main or upright casing section is indicated comprehensively by the numeral 1, and the horizontal component section generally by the numeral 2. The upright section 1 is amply proportioned to accommodate the sound board 3, the string frame 4 and the playing action (not illustrated). The upper half 5 of the casing section 1 is larger than the lower half 6, both with regard to horizontal width and lateral depth, and the ends of the upper portion 5 are somewhat recessed at the bottom as at 7-7 (see Figs. II and V) for a purpose to be presently explained. Stability of the upright casing section 1 is assured by providing the lower half 6 with forwardly extending feet 8, these as well as the rear base corners of the section, being equipped with ball casters 9. As shown, the frontal panels 10, 11 of the upper and lower halves 5, 6 of the casing section 1, are separated by an interval 12 for reception of the key frame after a manner hereinafter disclosed.

The horizontal component section 2 of the casing provides the console 13 which

affords the key bed 14 support, and has hinged to it the cover leaves 15, 16 that may be swung down, as shown in Fig. III to enclose the keys 17. The side cheeks 18 of the casing section 2 are extended horizontally rearward beyond the portion 13 as indicated at 19, and the whole is made self supporting by legs 20, 20 which are secured at the front corners and back ends of horizontals or sills 21 providing basal reinforcement for the said cheeks 18. The casing section 2 also carries a lyre frame 22 which is suspended centrally, and affords support for the control pedals 23 after standard practice in grand piano construction.

In assembling the piano casing, the extended cheek portions 19 of the horizontal section 2 are brought into overlapping relation with the recessions 7 at the ends of the upright section 1, as shown in Fig. I, the interval 12 receiving the protruding back part of the key bed 14 as will be obvious by reference to Fig. IV. Incidentally it is to be noted that the reinforcing sills 21 of the cheeks 18 are accommodated beneath the overhang shoulders that mark the division between the upper and lower halves 5-6 of the upright casing section 1, and that the rear legs of the component section 2 are afforded room by reason of the longitudinal contraction of the lower half 6 of the main casing section 1. As a means to secure the two casing sections 1, 2 in assembled relation I prefer to use screws 24 (Figs. IV and V) which are preferably applied from the inside so as to be concealed from view at the exterior.

A piano casing constructed in accordance with my invention is obviously capable of considerable variation in simulating different period types of spinnet key consoles (one such being herein exemplified), the great variation attainable enabling an upright casing (otherwise more or less objectionable in appearance) to be beautified and rendered more attractive from an artistic point of view. The contention that difficulty might be experienced in moving on account of the greater extension of the key console, is, it will be appreciated, entirely offset by virtue of the separable construction of the casing. Another important advantage in connection with my invention is that as a consequence of setting back the lower portion 6 of the upright casing section 1, I am able to secure greater lateral depth beneath the key board

whereby the player is given just so much more leg room for convenience and comfort. This feature also tends to beautify the instrument in that it relieves the frontal flatness which is objectionable in upright piano casings as ordinarily constructed.

Having thus described my invention, I claim:

1. The combination, in a piano, of an upright action accommodating section embodying upper and lower halves with intervening side recessions, and a self-supporting horizontal section including the key-bed, said horizontal section having extended side cheeks interfitting the recessions in the upright section and, sustaining legs at the front corners and back ends of the side cheeks.
2. The combination, in a piano, of an upright action-enclosing section comprising upper and lower halves of greater and lesser width and depth respectively, and a self-supporting horizontal console section having extended side cheeks interfitting complementary recessions in the ends of the upright section with sustaining legs at the front corners and back ends of the side cheeks.
3. The combination, in a piano, of an upright action-enclosing section comprising

upper and lower halves, the upper being of greater width and depth than the lower and separated by an open space, a self-supporting horizontal console section having extended side cheeks and including the key-bed, the back of the key-bed being accommodated in the open space aforesaid with the extended side cheeks interfitting complementary recessions in the ends of the upright section, and sustaining legs secured at the front corners and back ends of the aforesaid side cheeks.

4. In a piano of the type described, an upright action accommodating section comprising upper and lower halves, the upper half being of greater width and depth than the lower with the ends horizontally recessed, and said halves being separated by an open interval along the front panels only.

5. In a piano of the type described, a horizontal console section accommodating the key-bed and having rearwardly extended side cheeks with supporting legs at the front of said section and at the back ends of the side cheeks.

In testimony whereof, I have hereunto signed my name at Philadelphia, Pennsylvania, this 9th day of January, 1925.

CLARENCE F. BREY.
